UNITED STATES PATENT OFFICE.

THEODORE HOFSTATTER, JR., OF NEW YORK, N. Y.

SOFA AND LOUNGE.

SPECIFICATION forming part of Letters Patent No. 247,350, dated September 20, 1881.

Application filed February 10, 1881. (No model.)

To all whom it may concern:

Be it known that I, THEODORE HOFSTATTER, Jr., of the city, county, and State of New York, have invented a new and useful Improvement 5 in Sofas and Lounges, of which the following is a specification.

My invention relates to sofas and lounges having their head or end portions adjustable for varying the inclination.

10 The object of my invention is to construct such adjustable lounges with simple and durable mechanism, which I accomplish by the use of pivoted latch-bars, racks, and cams, combined with a head-frame fitted to swing on the 15 main frame of the lounge or sofa.

In the accompanying drawings, Figure 1 is a vertical longitudinal section of one end of a lounge containing my improvements; and Fig. 2 is a vertical transverse section on line *x x* 20 of Fig. 1.

Similar letters of reference indicate corresponding parts.

a a are the side rails, and *b b* the end rails, of the main frame.

25 *A* is the adjustable head or end, composed of side bars, *c c*, and outer cross-bar, *d*. The side bars, *c*, have their lower ends formed to enter between the rails *a* of the main frame, and are attached thereto by pins *e*, so that the 30 head may swing from a vertical to a horizontal position, as shown by dotted lines in Fig. 1. There may be a similar head at each end of the main frame, so that the article shall serve with both ends raised as a sofa; or either end 35 may be turned down to the horizontal position to form a lounge, either right or left hand, as required.

40 *f f* are the latch-bars, hung at the inner sides of bars *c* by pivot-pins *f'*. The bars *c* are formed with grooved lugs that receive the latch-bars, and through these lugs the pivot-pins *f'* pass.

45 *g g* are curved racks, fixed on side rails, *a*, in position for being engaged by the bent lower ends of bars *f*.

h is a shaft, fitted in bars *c*, across the outer 45 part of head *A*, and carrying cams *i i* contiguous to the upper ends of latch-bars *f*. As shown, the shaft *h* passes through latch-bars *f*, but that is not essential.

k k are springs, fitted between bars *c* and 50 latches *f*, and tending to move the latter into engagement with racks *g*. The cams *i* are shaped to move the upper ends of latch-bars *f* outward when the shaft *h* is turned. To adjust the head *A* the shaft will be turned to 55 disengage the latches from the racks, and the head can then be swung on its pivot *e*. Then by turning the shaft a quarter revolution latches *f* are released and engage with racks *g*. For convenience of operating the shaft it is provided with knobs or handles *l*.

This mechanism is of durable character and is not liable to get out of order. The lounge or sofa will be suitably upholstered, so that the adjustable head may move as described, 65 and in such manner that when the head is horizontal it forms an extension of the lounge on the same level. This may be readily done.

The cams may be of different form from those shown, and the shaft *h* placed in a different 70 position with relation to the latch-bars. I do not limit myself in these particulars.

Having thus described my invention, I claim as new and desire to secure by Letters Patent--

The combination, with the head *A*, adapted 75 to swing on the main frame, of the end-bent spring-held latch-bars *f*, fulcrumed on the inner sides of bars *c*, the curved racks *g*, fixed on the sides of rails *a*, and the shaft *h*, carrying cams *i* in contact with the upper ends of said latch-bars, as and for the purpose specified.

THEODORE HOFSTATTER, JR.
